UNITED STATES PATENT OFFICE

153,315

DESIGN FOR A HELICOPTER

Frank N. Piasecki, Lansdowne, Pa., assignor to
Piasecki Helicopter Corporation

Application March 13, 1947, Serial No. 137,602

Term of patent 14 years

(Cl. D71—1)

To all whom it may concern:

Be it known that I, Frank N. Piasecki, a citizen of the United States of America, residing at Lansdowne, in the county of Delaware and State of Pennsylvania, have invented a new, original, and ornamental Design for a Helicopter, reference being had to the accompanying drawings, forming a part thereof, of which the following is a specification.

Figure 1 is the side elevational view of a helicopter, showing my new design as it would appear on the ground.

Figure 2 is a front elevation view of the same.

Figure 3 is a top plan view of the same.

Figure 4 is a perspective view of the same.

Figure 5 is a rear elevational view of the same.
I claim:

The ornamental design for a helicopter, as shown.

FRANK N. PIASECKI.
